WALTER KUNZE, OF BERLIN, GERMANY, ASSIGNOR TO RADIO CORPORATION OF AMERICA, A CORPORATION OF DELAWARE

BEAT-FREQUENCY HETERODYNE RECEIVER ARRANGEMENT

Application filed December 18, 1926, Serial No. 155,617, and in Germany October 7, 1925.

An application for this invention has been filed in Germany on October 7, 1925.

This invention relates to beat frequency reception and the same, both as to its construction and mode of operation together with the objects and advantages thereof, will best be understood by reference to the following description taken in connection with the accompanying drawing in which

10 Fig. 1 is a front view of a panel showing in what manner the several condenser knobs are arranged with respect to each other,

Fig. 2 is a plan view thereof, and

15 Fig. 3 is a schematic sketch in plan elevation of the arrangement.

In reception based upon the superheterodyne principle, it is necessary to have an oscillation circuit tuned to the incoming wave, and in addition thereto another oscillation 20 circuit which is connected with a local oscillator and which must be so tuned that there results a definite frequency difference, so called, intermediate or beat frequency. If for this purpose, therefore, condensers are 25 used in which there exists a linear interrelationship between the angle of rotation and the resultant frequency, it is possible to so mount the two condensers that by rotating one of them, the second condenser may simultaneously be adjusted. A particularly 30 simple manipulation of a superheterodyne receiver apparatus may be obtained if the spindle of the condenser which accomplishes the adjustment to the incoming wave-length 35 is provided with a concentric bore for receiving the spindle of the condenser which serves to regulate the beat frequency, the amount of relative rotation of the two condensers thus determining the beat frequency.

40 As shown to the left in Fig. 1, the relative position of the knob for the oscillation circuit condenser and that of the tuned circuit condenser for the incoming wave is indicated, and the beat frequency reading is indicated 45 by the calibrated scale on the condenser head

or knob of the incoming wave condenser in terms of meters. The knob of the tuned circuit condenser in turn is moved over a dial upon the panel, this dial being calibrated in terms of wave-length of the incoming wave. 50 Manipulation becomes particularly simple and easy on account of the fact that the beat frequency is adjusted at will by turning the upper condenser knob (oscillator) upon the scale of the lower condenser knob (for incoming wave), whereupon the combination or system is tuned to the wave to be received according to the calibration provided therefor.

Another point in connection with superheterodyne reception is to amplify the intermediate or beat frequency by a beat-frequency amplifier. This is ordinarily effected by the use of a transformer-coupled radio frequency amplifier, whose grid circuits are tunable by the aid of rotary condensers. Now, if the rotary condensers required therefor are seated upon a joint spindle whose knob is shown on the right-hand side in Fig. 1, then the entire beat frequency amplifier can be adjusted or tuned to the desired beat frequency by one manipulation. For this purpose a calibration of the scale in terms of wave length or frequencies is also provided. The variation or variability of the beat frequency offers this great advantage, that in the presence of any interfering transmitters, the beat frequency can be changed immediately so that operations can be liberated from such disturbing actions. It has been found in the case of superheterodyne receivers which are set to a definite beat frequency that they are often troubled by stations which happen to transmit on a wave equal to this beat frequency. Without the provision of the jointly adjustable condensers, in the case of a three-stage beat-frequency amplifier, for example, it would be necessary to tune consecutively three condensers to the desired beat frequency. Where circuits involving feeble damping are concerned, this is attended with 85 90

serious difficulties seeing that the tuning must be very sharp in order that an adequately large amplification may be attained. Hence, the operating knobs according to the disclosures of this invention are reduced to one knob.

Further, in the attempt to locate a certain station, it has heretofore been necessary to simultaneously manipulate the condenser for the incoming wave and the heterodyne (local-oscillator) condenser. But according to the invention, this manipulation is also reduced to the operation of a single knob. In case of variation of the beat frequency, ease of manipulation is preserved by the use of calibrated scales.

Having thus described my invention, I claim:

1. In a superheterodyne receiving system, a dial for indicating the incoming signal frequency, a calibrated scale of intermediate beat-frequencies carried by said dial, and a rotary knob, controlling the local oscillator frequency, having an index, arranged to slide over said calibrated scale to indicate directly the intermediate beat-frequency resulting from the conjoint action between the incoming signal frequency and the local oscillator frequency.
2. In a superheterodyne receiving system having a rotary condenser for tuning the input circuit to the incoming wave, a rotary condenser for controlling the frequency of the local oscillator circuit, a dial having a calibrated scale of intermediate beat-frequencies thereon operatively connected with the incoming wave condenser for adjusting the same and indicating the wave to be received, and a rotary knob, controlling the oscillator condenser, having an index, arranged to slide over the calibrated scale to indicate directly thereon the intermediate beat-frequency resulting from the conjoint action between the input circuit and the oscillator circuit.
3. In a superheterodyne receiving system having an input circuit and a local oscillator circuit for producing intermediate beat-frequencies, a rotary condenser for tuning the input circuit, a second rotary condenser for tuning the local oscillator circuit, a dial operatively connected with said first condenser for adjusting said condenser to the incoming wave, and a dial, operatively connected with said second condenser, having an index, and rotatable on said first dial for adjusting the second condenser relative to the first to obtain the desired beat-frequency.
4. In a superheterodyne receiving system having an input circuit and a local oscillator circuit for producing intermediate beat-frequencies and a plurality of beat-frequency amplifier circuits, in combination, a rotary condenser for tuning the input circuit, a second rotary condenser for tuning the local os-

cillator circuit, a dial operatively connected with said first condenser for adjusting said condenser to the incoming wave, a dial, operatively connected with said second condenser, having an index, and rotatable on said first dial for adjusting the second condenser relative to the first to obtain the desired beat-frequency, a series of tuning condensers for beat-frequency amplifier circuits, and single means for varying said series of condensers.

WALTER KUNZE.
